UNITED STATES PATENT OFFICE

153,791

DESIGN FOR A SCRUB BUCKET DOLLY

Frank H. Gruettner, Buffalo, N. Y.

Application October 1, 1947, Serial No. 141,701

Term of patent 14 years

(Cl. D49—1)

To all whom it may concern:

Be it known that I, Frank H. Gruettner, a citizen of the United States, residing at Buffalo, in the county of Erie and State of New York, have invented a new, original, and ornamental Design for a Scrub Bucket Dolly, of which the following is a specification, reference being had to the accompanying drawing, forming part thereof.

Figure 1 is a top perspective view of a scrub bucket dolly, showing my new design, and

Figure 2 is an underside perspective view thereof.

I claim:

The ornamental design for a scrub bucket dolly, as shown.

FRANK H. GRUETTNER.
